UNITED STATES PATENT OFFICE.

WALTER E. PRUZAN, OF NEW YORK, N. Y.

DESIGN FOR A BRASSIÈRE.

59,772.

Specification for Design. Patented Nov. 22, 1921.

Application filed May 5, 1921. Serial No. 467,222. Term of patent 14 years.

To all whom it may concern:

Be it known that I, WALTER E. PRUZAN, a citizen of the United States, and resident of New York, borough of Manhattan, county of New York, State of New York, have invented a new, original, and ornamental Design for a Brassière, of which the following is a specification, reference being had to the accompanying drawing, forming part thereof.

showing my new design; Fig. 2 is a front view thereof in position for use, and Fig. 3 is a back view.

I claim:

The ornamental design for a brassière, substantially as shown.

Signed at New York, in the county of New York and State of New York, this 2nd day of May, 1921.

WALTER E. PRUZAN.
